UNITED STATES PATENT OFFICE.

CHARLES PHILLIPS, JR., OF PHILADELPHIA, PENNSYLVANIA.

TELEGRAPH TRANSMITTER.

1,407,572.

Specification of Letters Patent. Patented Feb. 21, 1922.

Application filed October 18, 1920. Serial No. 417,539.

To all whom it may concern:

Be it known that I, CHARLES PHILLIPS, Jr., a citizen of the United States, residing at Philadelphia, in the county of Philadelphia and State of Pennsylvania, have invented new and useful Improvements in Telegraph Transmitters, of which the following is a specification.

This invention relates to telegraphic transmitters and it has more particular reference to devices such as are usually employed for transmitting messages in the Morse, naval or other similar code, and it has for its main object to provide a code transmitter which will facilitate to a considerable degree the transmission of telegrams, messages and so forth.

Another object of this invention is the provision of a telegraphic or code transmitter by the use of which a comparatively inexperienced person can transmit a message mechanically in a simple, rapid and accurate manner by merely striking the keys of a keyboard, each separate key whereof corresponds to a particular sign or character of the code or alphabet that is used, whether it be a Morse, naval or otherwise.

A still further object of my invention is to provide a telegraphic or code transmitter by the use of which the operator is provided with an accurate visual record of each letter, character or symbol, word or message transmitted, whereby a great saving of time and labor is effected in that corrections are reduced to a minimum.

With the foregoing and other objects in view as will later on be more apparent my invention consists essentially in the provision of a series of key-stems connected to— or integral with—type levers similarly mounted and actuatable in like manner to the keys of an ordinary type-writing machine, each said key-stem being formed with dot-and-dash (or other suitable) insularly located contacts with which cooperate a spring influenced circuit closer when the key is depressed; whereas on the return stroke of the key-stem said circuit closer is automatically held out of engagement with the said insularly located contacts.

In the further disclosure of the invention reference is to be had to the accompanying sheet of explanatory drawings constituting a part of this specification, and in which like characters of reference designate the same or corresponding parts in all the views.

Figure 1 is a fragmentary side elevation of a portion of a transmitting machine constructed in accordance with the principle of my invention, only such parts of the battery of keys being illustrated as are essential to a clear understanding thereof.

Figure 2 is a plan of the same.

Figure 3 is an enlarged side elevation of an individual transmitter key-stem and its associated parts.

Figure 4 is an elevation taken at right angles to the preceding figure.

Figure 5 is a sectional elevation of the same.

Figure 6 is a side elevation showing the transmitter key-stem with the circuit closer as held in the inoperative position during a part of the return stroke of said key-stem.

Figure 7 is a sectional plan taken on the line 7—7 in Figure 3.

Referring to the drawings I have shown my improved code transmitter as applied to an ordinary typewriting machine a portion of the frame whereof is designated by the numeral 10 and having the usual battery of keys 11, mounted on type levers 12, said machine being provided with a supporting member 13.

Securely attached to the supporting member 13 are a series of vertically depending guides 14 channel shaped in cross section as will be clearly seen on reference to Figure 6, each said guides 14 constituting a housing for square section key-stems 15 depending from the aforesaid type levers 12.

Referring now more particularly to Figures 3 to 7 inclusive, it will be seen that each depending guide 14 is formed on opposed sides with slots 16 into which project laterally disposed pins 17 on the key-stem 15 and serving to limit the up and down movement thereof as well as retaining said key-stem in operative connection relative to the guide. Extending rearwards through a slot 18 in the back of the guide 14, is a tongue or projection 19 for the purpose hereafter explained, and attached to said guide 14 is a flat spring 20 having an inwardly curved or arcuate portion 21, an outstanding part 22, and a turned over or latched upper end 23.

Pivoted on laterally projecting pintles 24 on the aforesaid guide 14 are opposed spaced levers 25 rigidly connected by a brace 26, and having secured between their forward ends a block of insulating material or hard rubber 27, and it is to be particularly noted

that the rear ends of said spaced levers 25 are extended sufficient to lie in the path of—and be engaged by—the aforesaid latched or turned over upper end 23 of the spring 20 5 as will be clearly understood by reference to Figure 6 and for the purpose later on fully set forth.

Secured to the forward end of the insulating block 27 as by a screw or pin 28 which 10 supports and holds the same firmly in place is a narrow springy tongue or make-and-break device 29; whereas at the rear end of said insulating block 27 there is provided a hook 30 for one end of a contractile spring 15 31, the other end whereof is connected to a bridge piece 32 on the guide 14.

Moulded or cut in the open face of the key-stem 15 are grooved or recessed portions 20 33 in which are firmly embedded fiber or other appropriate pieces of insulating material 34, which house and insulate code contacts 35 corresponding in length or proportion to the dots, dashes, or combinations thereof, constituting the particular code the 25 instrument uses or is adapted for.

Appropriate recoil springs 36 may be fitted beneath each key-stem 15 to ensure their instantaneous return after each depression, and a line wire 37 is conveniently attached 30 to a binding post 38 on the supporting member 13, and under the control of a switch in the usual manner.

From the foregoing description it will be readily seen that when each individual key 35 11 is in its normal or raised position that the free end of the springy tongue 29 reposes on the lower insulating insert 34 so that the circuit through the line wire 37 is broken or open; whereas when said key 40 11 is depressed in opposition to its recoil spring 36 the springy tongue 29 is traversed by the insular code contacts 35 one after another thus completing intermittent circuits through the instrument of duration 45 45 forming to the time of such passage there-over, breaks taking place as the tongue is traversed by the insulating material between said contacts. It is to be particularly noted that as each key 11 and its attached stem 50 15 is depressed to nearly its fullest extent the latched or turned over upper end 23 of the spring 20 is engaged by the outer ends 39 of the spaced levers 25 and sprung slightly away from the guide 14 until the 55 parts 39 and 23 assume latched engagement as shown in Figure 6. Thus it will be clearly seen that on the release of the key 11 and its automatic return by the recoil spring 36, re-

transmission of the particular signal or code character transmitted on the down-ward 60 travel of the key over the contacts 35 in reverse order is effectively prevented, release of the latch 23 and the outer ends 39 of the spaced levers 25 only taking place as the tongue 19 engages below and traverses the 65 arcuate portion 21 of the spring 20. This latter release permits the contractile spring 31 to function and retract the springy tongue 29 to the normal or position shown in Figures 3 and 5. 70

As the several and successive keys 11 are depressed the desired code words, letters or other signals will be transmitted to the other end of the line wire 37 where they may be received and recorded in any of the well 75 known ways.

Although I have confined this description more particularly to the means employed to transmit an individual character or signal, it will be readily understood by those skilled 80 in the art to which my invention appertains that its application to the entire battery of keys 11 will only be mere duplication. Furthermore, I wish it clearly understood that many slight changes may be necessary to 85 adapt said invention for the transmission of different codes, and I therefore do not confine myself to the precise details of construction shown and described, but deem myself at liberty to include all such reasonable 90 changes and other forms as may fairly fall within the scope of the appended claim.

Having described my invention what I claim as new and desire to secure by Letters Patent is:— 95

A telegraph transmitter comprising a spring influenced reciprocable key-stem having insular contacts thereon, a stationary guide housing said key-stem, means for limiting the movement of the key-stem in the guide, spring influenced spaced levers pivotally mounted on the stationary guide and supporting an insulated spring tongue circuit closer adapted to be traversed by the insular contacts when the key-stem moves 100 forwardly, a recoil latch member carried by the guide and having an offset and arcuate portions, said latch member holding the circuit closer out of engagement with the insular contacts on the return stroke of the 110 key-stem, and means on the key-stem for co-operation with the arcuate part of the latch member to release the circuit closer as the key-stem returns to normal position.

In testimony whereof I affix my signature. 115
CHARLES PHILLIPS, JR.
